UNITED STATES PATENT OFFICE

JULIUS RITTER, JR., OF RACINE, WISCONSIN, ASSIGNOR TO HARTMANN TRUNK COMPANY, OF RACINE, WISCONSIN, A CORPORATION OF WISCONSIN

WARDROBE HATBOX

Application filed November 20, 1929. Serial No. 408,500.

This invention relates to improvements in wardrobe hat boxes, of the type adapted to be used by women as hand luggage.

It is one of the objects of the present invention to provide a piece of hand luggage having a wardrobe section wherein is mounted an adjustable clothes rack arranged, when the box is opened, to be extended out of the wardrobe section for ready access and inspection of the apparel thereon, and adapted, when the box is closed, to occupy a very compact position within the wardrobe section.

A further object of the invention is to provide in a hat box of the class described having an adjustable clothes rack, releasable means cooperating with the clothes rack for holding the clothes rack in its folded position within the wardrobe section and maintaining apparel in proper position on the clothes rack.

A further object of the invention is to provide a wardrobe hat box of convenient size and proportions which has a relatively large capacity and arranged so that the wardrobe section clothes rack may be very easily and quickly loaded or unloaded.

A further object of the invention is to provide a wardrobe hat box which is of very simple construction, is strong and durable, and is well adapted for the purposes described.

With the above and other objects in view the invention consists of the improved wardrobe hat box and its parts and combinations as set forth in the claims, and all equivalents thereof.

In the accompanying drawings in which the same reference characters indicate the same parts in all of the views:

Fig. 1 is a longitudinal sectional view through the wardrobe hat box in open position with the clothes rack shown swung outwardly of the wardrobe or cover section;

Fig. 2 is a front view of the hat box in open position with the clothes rack held flatly within the wardrobe or cover section and the latter secured in an upright relation with respect to the body section;

Fig. 3 is a longitudinal vertical sectional view of the hat box position shown in Fig. 2

only with the strap device for the clothes rack released with the latter swung to a position free of the outer end portion of the wardrobe or cover section;

Fig. 4 is an enlarged detail sectional view 55 taken on line 4—4 of Fig. 2;

Fig. 5 is an enlarged, fragmentary, detail sectional view taken on line 5—5 of Fig. 2; and

Fig. 6 is an enlarged detail sectional view 60 taken on line 6—6 of Fig. 1.

Referring now more particularly to the drawings it will appear that the improved wardrobe hat box includes in general a substantially square body section 8, U-shaped 65 in cross-section, and a shallower, substantially square cover or wardrobe section 9, also U-shaped in cross-section and hinged to the body section by leather or fabric hinge strips 10.

The body section 8 is formed of a bottom 11, a relatively narrow front 12, a somewhat higher rear 13, and opposed forwardly, downwardly inclined sides 14 between the front and the rear. The interior of said body 75 section is divided by a transverse partition 15, positioned relatively close to the front 12, into a narrow front compartment for shoes and small articles of apparel, and a large compartment for hats and other articles. Secured to opposite inner side walls of the large compartment are pockets 16, while a pocket 17 is secured to the front surface of the partition 15.

The hinge connection 10 is between the 85 upper edge of the rear 13 of the body section and a narrow rear flange 18 of the cover section 9. In addition to said flange 18 said cover section includes a flat top 19, a front 20, somewhat higher than the rear flange 18, 90 and a pair of opposed sides 21 between the flange 18 and the front 20, said sides being rearwardly or inwardly tapered.

Pivotedly or foldably mounted with respect to the cover section 9 is a clothes rack 95 comprising a pair of supporting arms 22 and a top bar 23 joining the upper or outer ends of the same. The lower end portions of the arms 22 are formed as brackets 22' with lower angular flanges 24 formed with openings 100

25, for the purpose hereinafter to be explained. The bracket portions 22' of the arms 22 are pivotally secured to opposite inner portions of the sides 21 of the cover section by pivot bolts 26.

5 A pair of flexible straps 27 are secured at one pair of ends to opposite inner, intermediate side portions of the sides 14 of the body section. The other end portions of said 10 straps are releasably secured, by means of snap fasteners 28, to opposite, inner, intermediate side portions of the sides 21 of the cover section. Inwardly a short distance from the last-mentioned ends of the straps, 15 the same are secured to the arms 22 of the clothes rack. The manner in which said straps are secured to the arms 22 is shown in detail in Fig. 6 and it will be noted that each arm carries a band 29 and a strap is 20 clamped between said band and a depressed portion 30 of the arm.

For the purpose of maintaining the clothes 25 rack in proper position within the cover section and for holding garments in place on the clothes rack, a strap device or harness 31 is provided, which is substantially in the shape of an H, as shown in Fig. 2. Said harness is formed of fabric with inner elastic strips 32 within side portions of the fabric, as shown in Fig. 4, to give yieldability 30 or elasticity to the entire harness. The upper end portions of the harness are secured within the upper or free end portion of the cover section, while the lower end portions of the harness carry hooks 33 for releasable engagement with the openings 25 in the brackets 22'.

40 In open position the wardrobe hat box may assume the position shown in Fig. 2 and to permit the clothes rack to be swung outwardly with respect to the cover section to the position shown in Fig. 3 the hooks 33 of the harness must be disengaged and the harness moved to an out of the way position 45 rearwardly of the clothes rack or over the top edge of the cover section. In this position of the clothes rack and cover section, garments may be readily hung on or removed from the bar 23 of the clothes rack. It is 50 also expeditious, in this position, to drape garments over the top of the cover section, and then when the garment rack is moved inwardly, the garments may be folded onto the bar 23 in correct position very easily. If 55 the snap fasteners 28 of the flexible straps 27 be released, the cover section may be widely opened, as shown in Fig. 1, and the clothes rack will remain in a substantially vertical position.

60 When the hat box is packed and garments hung on the clothes rack said clothes rack is folded closely into the confines of the cover section, and it is so held, and the garments held thereon against dislodgment by the harness 65 31 which is drawn over the front of the

clothes rack and hooked to the brackets 24, as shown in Fig. 2. The cover section may then be closed with respect to the body section and is so held by suitable latches 34. A handle 35 is secured to the body section for 70 convenience in carrying the hat box.

If the garments suspended from the bar of the clothes rack are somewhat long, their lower end portions may be extended into the inner portion of the large compartment of 75 the body section. The formation of the cover section with inwardly tapered side walls is advantageous in that clothes may hang from the clothes rack down the height of the cover section and into the body section close to a 80 substantially level packing surface. Also, said cover construction makes the lower edges of garments on the rack readily accessible and visible when the hat box is opened.

85 From the foregoing description it will be evident that the improved wardrobe hat box provides a convenient and commodious piece of hand luggage, is strong and durable, and is well adapted for the purposes described.

90 What I claim as my invention is:

1. A luggage case, comprising a body section, a cover section hingedly connected thereto, a clothes rack pivotally mounted within the inner corner portions of the cover section and extending therein lengthwise of the cover section and movable outwardly of the outer end portion of the cover section when the latter is open, and flexible means connected to the body section, the clothes rack and the cover section for maintaining a certain relationship between said members when the case is open.

105 2. A luggage case, comprising a body section, a cover section hingedly connected thereto, a clothes rack pivotally mounted within the inner corner portions of the cover section and extending therein lengthwise of the cover section and movable outwardly of the outer end portion of the cover section when the latter is open, and flexible means connected between the body section and the clothes rack for maintaining the latter perpendicularly to the former when the case is open and also releasably connected with the cover section.

110 3. A luggage case, comprising a compartmental body section having slanting sides so as to be higher at one end than at the opposite end, a flanged cover hinged to the free edge of the higher end of the case and having its flanges reversely slanted relative to the sides of the body section, a clothes rack within said cover section, said clothes rack comprising a pair of arms pivotally connected at one pair of ends to the inner corner portions of the cover section, and a bar joining the free end portions of said arms, said clothes rack being movable to a position entirely within the cover section and also being movable to a position outwardly of the cover 125 130 135

section when the latter is open, flexible means connected between the body section and the clothes rack for maintaining the latter perpendicularly to the former when the case is
5 open and also releasably connected with the cover section, and a flexible retaining member secured within the outer end portion of the cover section and adapted to be stretched over the clothes rack to hold it flatly within the
10 cover section, said retaining member having means at its free end portion for releasable hooking engagement with inner interior portions of the cover section.

4. A luggage case, comprising a body section, a cover section hingedly connected thereto, a clothes rack pivotally mounted within corner portions of the cover section and movable outwardly of the outer end portion of the cover section when the latter is
15 open, and a flexible retaining member secured within the outer end portion of the cover section and adapted to be stretched over the clothes rack and garments thereon to hold both the clothes rack and garments within
20 the cover section, and having means at its unsecured end portion for quickly releasable engagement with inner interior portions of the cover section.

25 In testimony whereof, I affix my signature.
